WINDOW CONSTRUCTION

Christian M. Verhagen, Elkhart, Ind., assignor to
The Adlake Company, Chicago, Ill., a corpora-
tion of Illinois

Original application April 29, 1936, Serial No.
76,919. Divided and this application July 2,
1938, Serial No. 217,291

5 Claims. (Cl. 189—64)

One of the objects of this invention is to provide a window of improved construction which is equipped with novel means for securing it in a window opening, which securing means permits the window to be effectively sealed in position and also permits of its ready installation and removal.

Another more specific object of the invention is to provide a double glass window of the character described in which the outer sash is fixed and the inner sash is hinged or otherwise movably mounted on special inwardly extending flanges formed on the outer sash, which flanges constitute part of the above mentioned securing means.

Other objects and advantages of the invention will be apparent to those skilled in the art upon a full understanding of the construction, arrangement and operation of the improved window.

This application is a division of my earlier application, Serial No. 76,919, filed April 29, 1936.

Two forms of the invention are presented herein for the purpose of exemplification, but it will of course be appreciated that the invention is susceptible of embodiment in other structurally modified forms coming equally within the scope of the appended claims.

In the accompanying drawings:

Fig. 1 is an inside face view of a double glass window constructed in accordance with the invention;

Fig. 2 is a vertical section through the window, taken on the line 2—2 of Fig. 1;

Fig. 3 is a horizontal section, taken on the line 3—3 of Fig. 1;

Fig. 4 is a perspective view of a portion of one of the side rails of the inner sash, showing the way in which that rail is detachably secured to the corresponding rail of the outer sash;

Fig. 5 is a horizontal section through the two rails, taken on the line 5—5 of Fig. 4;

Fig. 6 is a similar section, taken on the line 6—6 of Fig. 4;

Fig. 7 is a similar section, taken on the line 7—7 of Fig. 4;

Fig. 8 is a side view of a tool suitable for use in shifting the locking strips; and

Fig. 9 is a sectional view which corresponds to Fig. 5 but illustrates a modified form of the invention.

In the window structure which is illustrated in Figs. 1 to 7 inclusive the outer metal sheathing 10 of the car is provided with a rectangular opening 11 at the location of the window. This open-

ing is surrounded, on the inside of the car, with a metal frame 12 which is set back from the edge of the opening in order to leave a margin 13 of the sheathing exposed. The window includes 5 a fixed outer sash 14 which is positioned against the margin 13 of the sheathing and a movable inner sash 15 which is positioned against the inner face of the outer sash. The rails 16 of the outer sash are provided with L-shaped flanges 17 composed of portions 18 which extend inwardly 10 from the edges of the rails and portions 19 which project toward the frame 12 from the inner extremities of the portions 18. The portions 18 form a frame 20 for the reception of the inner 15 sash 15. The portions 19 lap flanges 21 on angle strips 22 secured to the frame 12, and are fastened to the flanges 21 by means of screws 23. The outer faces of the rails 16 of the outer sash are provided with dovetailed grooves 24 in which 20 packing strips 25 of soft rubber or other suitable material are seated. When the screws 23 are drawn up, the packing strips 25 are compressed between the rails 16 and the margin 13 of the sheathing about the opening, whereby to produce 25 a tightly sealed weatherproof joint between the outer sash and the sheathing.

The inner sash 15 is fastened at its upper edge to the upper part of the frame 20 on the outer sash 14 by means of a hinge 26 which extends 30 continuously the full width of the sash. This hinge permits the inner sash to be swung inwardly and upwardly away from the outer sash when the opposed surfaces of both sash require cleaning.

35 The outer faces of the rails 27 of the inner sash are grooved, like the outer faces of the rails of the outer sash, and contain strips 28 of soft rubber or other suitable material which are compressed against the inner faces of the rails of the outer sash when the inner sash is swung down 40 into its closed position. The side and bottom rails of the inner sash are provided with flanges 29 which slightly lap the flanges 19, and the side rails of the inner sash are provided at the bases 45 of the flanges 29 with narrow slots 30 in which closely fitting flanges 31 on locking strips 32 are shiftable mounted.

The locking strips 32—which constitute the improved means for detachably clamping the inner sash against the outer sash on the interposed sealing strips 28—are characterized by flanges 33 which are positioned flatly against the sides of the frame 20 on the outer sash. These flanges are secured to the edges of the side rails of the inner sash, in slightly spaced relation to the side

rails, by two or more screws 34 in the side rails which have conical heads 35 which fit between the beveled edges of vertically elongated slots 36 in the flanges 33. The screws 34 limit the extent to which the locking strips 32 can be shifted upwardly or downwardly with respect to the side rails of the inner sash, and they also adjustably limit the extent to which the locking strips can move away from the side rails. The locking strips 32 are forced away from the side rails of the inner sash as far as the heads 35 of the screws 34 will permit, by two or more leaf springs 37 which are secured to the flanges 33 of the locking strips by rivets 38 and bear resiliently against the side rails.

The flanges 33 of the locking strips are provided with two or more bayonet slots 39 which open toward the outer sash and coat with pins 40 which are mounted in the sides of the frame 20 on the outer sash and project toward the sides of the inner sash. The pins 40 are provided with enlarged button-like heads 41 which engage with the rear faces of the flanges 33 and prevent the latter from working away from the sides of the frame 20 after the locking connection has once been established. The slots 39 have inclined edges 42 near their entrances and have slightly indented edges 43 at their ends, with the result that when the inner sash is closed down with the entrances of the slots in the strips in register with the pins, and the angle strips shifted downwardly, the inclined edges 42 of the slots will cam against the pins and draw the inner sash into its fully closed position, after which the indented edges 43 will register with the pins and seat the same enough to yieldingly resist any movement of the strips in the opposite direction. In this way both sides of the inner sash will be drawn up uniformly into sealed association with the outer sash.

In fastening or unfastening the inner sash 15 the locking strips 32 are shifted in either direction by a tool 44, on the order of the one shown in Fig. 8. The tool is inserted through a vertically elongated slot 45 in the flange 29 of the side rail 27, and through a relatively short slot 46 in the flange 31 of the locking strip to be moved, after which a notch 47 in the end of the tool is brought into engagement with a stud 48 on the frame 20. The stud 48 projects toward the inner sash through a notch 49 in the flange 33 of the locking strip. When the tool is now swung upwardly or downwardly, the stud 48 will act as a fulcrum for the tool and one of the side edges 50 of the same will engage with the opposed end of the slot 46 in the locking strip and cause the latter to shift up or down, depending on whether the tool is being swung upwardly to unfasten the inner sash or swung downwardly to fasten the same.

In the modification which is shown in Fig. 9 the locking strip 51 is arranged with the flanges 52 thereof in lapped association with the inner face 53 of the inner sash rather than within a groove provided in the edge of the inner sash as in the previously described embodiment. In all other respects the two constructions are substantially the same.

The locking strips have been described as applied to the two side edges of the inner sash which are disposed at right angles to the hinged edge, but it will of course be understood that an additional locking strip might also be applied to the edge opposite the hinged edge, or else a single locking strip applied to that edge alone,

with good results. Furthermore, the hinged connection of the inner sash with the outer sash might be omitted and the inner sash merely hooked into position or detachably connected in any other manner with the outer sash. The locking strips, although preferably carried by the inner sash, could obviously be applied over the edges of the inner sash as separately removable elements, without being actually fastened thereto.

While the improved window structure is particularly suited to air-conditioned railway cars, it will of course be appreciated that it can be used to advantage in any place where a double glass window is desired.

I claim:

1. In car window construction, the combination with the outer sheathing of a car, having a rectangular opening therein, and a frame set back from the opening on the inside of the car to provide a margin of the sheathing exposed about the opening, of a completely self-contained sash within said frame having rigid side rails overlying the exposed margin, a pane of glass mounted within glazing grooves in said side rails, compressible packing strips located between the rigid side rails of the sash and said margin, and extensions fixedly associated with the rigid side rails in spaced relation to the sheathing and adjustably connected with the frame for drawing the rigid outer wall of the sash up into tightly sealed association with the sheathing.

2. In car window construction, the combination with the outer sheathing of a car, having a rectangular opening therein, and a frame set back from the opening on the inside of the car to provide a margin of the sheathing exposed about the opening, of a fixed outer sash within the frame having rigid side rails overlying the exposed margin at the sides of the opening, sealing strips located between the side rails of the sash and said margin, the side rails of said outer sash being provided adjacent their peripheries with rigid inwardly extending flanges, an inner sash removably positioned between and detachably secured to said flanges, and clamping means acting between said flanges and the set-back frame for drawing the rigid outer wall of the outer sash up tightly against the margin of sheathing exposed within the frame.

3. In car window construction, the combination with the outer sheathing of a car, having a rectangular opening therein, and a frame set back from the opening on the inside of the car to provide a margin of the sheathing exposed about the opening, of a fixed outer sash within the frame having rigid side rails overlying the exposed margin at the sides of the opening, sealing strips located between the side rails of the sash and said margin, the side rails of said outer sash being provided adjacent their peripheries with rigid inwardly extending flanges, an inner sash removably positioned between and detachably secured to said flanges, angle strips secured to the sides of the set-back frame, outturned flanges on the inner edges of the inwardly extending flanges of the outer sash, and screws extending through said outturned flanges into the angle members on the set-back frame for drawing the rigid outer wall of the outer sash tightly against the margin of sheathing exposed within the frame.

4. In car window construction, the combination with the outer sheathing of a car, having a

rectangular opening therein, and posts at opposite sides of the opening set back from the edges thereof to provide exposed margins of the sheathing, of a completely self-contained sash between the posts having rigid side rails overlying the exposed margins, a pane of glass mounted within glazing grooves in said side rails, sealing means located between the side rails and said margins, means fixedly associated with the rigid side rails of the sash in spaced relation to the margins of the sheathing for mounting the sash in register with the opening, and means adjustably connecting said last mentioned means with the posts for drawing the rigid outer wall of the sash up into tightly sealed association with the sheathing.

5. In car window construction, the combination with the outer sheathing of a car, having a

- rectangular opening therein, and posts at opposite sides of the opening set back from the edges thereof to provide exposed margins of the sheathing, of a completely self-contained sash between the posts having rigid side rails overlying the exposed margins, a pane of glass mounted within glazing grooves in said side rails, sealing means located between the side rails and said margins, integral flanges on the rigid side rails of the sash 10 in substantially spaced relation to the margins of the sheathing, formations on the posts in overlapping and slightly spaced relation to said flanges, and screws extending through said flanges into said formations for drawing the rigid outer wall of the sash up into tightly sealed association with the sheathing.

CHRISTIAN M. VERHAGEN.
